DISPLAY SIGN FRAME

Lawrence G. White, New York, N. Y., assignor to The National Shawmut Bank of Boston, Boston, Mass., a banking corporation

Application March 5, 1954, Serial No. 29,378

Term of patent 14 years

(Cl. D1—12)

To all whom it may concern:

Be it known that I, Lawrence Grant White, a citizen of the United States, residing at New York, in the county of New York and State of New York, have invented a new, original, and ornamental Design for Display Sign Frame, of which the following is a specification, reference being had to the accompanying drawing, forming a part hereof, wherein

Fig. 1 is a front elevation of a display sign frame showing my new design; and

Fig. 2 is a view in side elevation.

I claim:

The ornamental design for a display sign frame, as shown.
